UNITED STATES PATENT OFFICE.

FRANCIS A. JACOBS, OF WARREN, OHIO, ASSIGNOR, BY MESNE ASSIGNMENTS, TO CHICAGO-CLEVELAND CAR ROOFING COMPANY, OF CHICAGO, ILLINOIS, A CORPORATION OF DELAWARE.

CAR ROOF.

Application filed October 14, 1924. Serial No. 743,521.

This invention relates in general to improvements in freight car roofs and more particularly to improvements in the class of car roofs usually designated as "outside metal roofs", which outside metal roof is movably or flexibly positioned on the car so as to cover the wooden sheathing or inside wooden roof of the car; and objects of the invention are the provision of a metal-
 5 roof capable of movement in harmony with the motion of the car without the necessity of providing mullions to prevent the roof from shifting; the provision of anchors for such car roofs which are not exposed
 10 to the elements and which are arranged to hold the sheets from upward movement and from too great longitudinal movement; the provision of a roof which is capable of simple manufacture at a reasonable cost and
 15 which can be readily applied on the car without the necessity of specially skilled workmen and which when so applied will be weathertight and not require frequent repair and replacement; and such other objects and advantages of the invention as are found to obtain in the structure hereinafter set forth and claimed.

In the accompanying drawings forming a part of this specification, and showing, for purposes of exemplification, a preferred form and manner in which the invention may be embodied and practiced, but without limiting the claimed invention specifically to such illustrative instance or instances:—

Figure 1 is a top plan view of a car roof embodying the invention, parts being broken away for better illustration.

Fig. 2 is a vertical cross-section taken on the line 2—2 of Fig. 1.

Fig. 3 is a vertical cross-section taken on the line 3—3 of Fig. 1.

Fig. 4 is a top plan view of a portion of the eaves corner of a roof sheet.

Fig. 5 is a top plan view of a roof anchor.

Fig. 6 is a side elevational view of the same.

Fig. 7 is a section taken on the line 7—7 of Fig. 5.

Fig. 8 is a vertical cross-section taken on the line 8—8 of Fig. 1.

On the drawings, 10 indicates the wooden side plates that extend longitudinally of the car and 11 is the inside wooden roof

sheathing. 12 is the side sheathing of the car, the upper edge of which is flush with the upper surface of the adjacent side plate. 13 is the side fascia, the upper edge of which is flush with the upper surface of the side sheathing 12. The outer edge of the roof sheathing 11 extends over the side sheathing and protrudes over a portion of the side fascia 13. The eaves edges of the roof sheathing 11 are gained out at 14 to receive a metallic flashing 15 whose inner edge terminates in an upwardly projecting open return bend hook 16 whose upper surface is below the plane of the top of the ungained roof sheathing and the flashing is flanged downwardly at 17 to enclose the edges 18 of the roof sheathing and is then bent outwardly at 19 over the top surface of the side fascia where it terminates in a depending flange 20 secured to the outer side of the side fascia.

Roof sheets 21 are disposed on opposite sides of the ridge 22 of the roof, said roof sheets having inverted U-shaped ridge flanges 22' lapped one over the other and side flanges 23, said side flanges 23 consisting of an upwardly extending inwardly inclined portion 24 terminating in a downwardly extending portion 25 spaced from the portion 24 and the main body 26 of the roof sheet. Said side flanges 23 terminate at a point 27 short of the eaves edge of the roof and the unflanged portion of the sides of the roof sheets are extended to form extensions or ears 28. The eaves edges of said roof sheets are flanged downwardly at 29 and terminate in an outwardly pressed longitudinally extending rigidifying bead 30 that is arranged over the outwardly extending portions 19 of the flashing but out of contact therewith. The ears 28, flanges 29 and beads 30 of adjacent roof sheets are lapped one over the other at 31. Roof anchors 32 are provided, in the present instance, secured on the flashing at the eaves edge of the car, one between the sides of two adjacent roof sheets. These anchors consist of a top web 33 having depending inwardly inclined sides 34 spaced from each other to provide a space 35 and said sides terminate in outwardly extending flanges 36 spaced from each other and said flanges 36 are secured to the roof sheathing by means passing through the apertures 37 therein. One

end of each of said flanges 36 is bent downwardly at 38 to fit against the flange 17 of the flashing and is then bent outwardly at 39 to fit over the portion 19 of said flashing and the portion 39 terminates in a depending flange 40 that is secured to the side fascia. The lower ends of the sides 34 are cut away to provide slots 41 through which the lapped extensions or ears 28 pass and are loosely confined therein so that the roof sheets may partake of proper movement and yet be effectively held down on the roof sheathing and prevented from shifting.

Side seam caps 42 extend from ridge to eaves, said caps being of substantially tubular form and having curved sides 43 inwardly turned at their lower ends and terminating in upwardly extending flanges 44 spaced from each other and from the sides 43 and when assembled on the roof, the flanges 44 are arranged in the spaces provided between the portions 24 and 25 of the side flanges 23 of the roof sheets. These side seam caps enclose the sides of adjacent sheets and the anchor arranged therebetween at the eaves of the roof and as they are not connected with the anchors, the anchors may be positioned on the roof sheathing before the seam caps are applied and the anchors may and do hold the roof sheets down on the sheathing independently of the seam caps. The eaves ends of the side seam caps are closed by bending the top and the sides of the seam caps one over the other as shown at 45.

The ridge ends 46 of the side seam caps 42 are lapped at 47 and are secured together and to the wooden roof sheathing, as shown in Fig. 8, by a bolt 48 which passes through the usual running board saddle 49, inverted U-shaped ridge cap 51, lapped ridge ends 46 of the side seam caps 42, wooden roof sheathing 11 and longitudinally extending ridge pole 52.

From the foregoing it will be apparent that the roof sheets are securely held down in place in weathertight condition without requiring wooden mullions or outside clips and that the side seam caps and the anchors constitute the sole means between the sheets for spacing and holding the sheets in relative positions.

The invention as hereinabove set forth is embodied in a particular form of construction but may be variously embodied within the scope of the claims hereinafter made.

I claim:

1. In a car roof, in combination, roof sheathing; a flashing secured on said sheathing and having a portion depending over the side of the car; roof sheets disposed on opposite sides of the ridge of the roof, said sheets having side flanges terminating in downwardly directed portions spaced from the body of the sheet, said flanges extending

from the ridge to a point short of the eaves edge of the roof, the eaves edges of the roof sheets terminating in flanges depending over the side of the car, the unflanged portions of said sheets at their sides being extended to form ears, the ears of adjacent sheets being lapped; seam caps enclosing the side flanges of adjacent roof sheets; and anchors enclosed by said seam caps at the eaves ends thereof, said anchors having a top web and depending inwardly inclined sides spaced from each other that terminate in outwardly extending flanges spaced from each other and arranged on said flashing, one end of each of said flanges being bent downwardly and secured to the side of the car over said flashing, portions of said anchor sides being cut away to provide slots into which the ears of adjacent roof sheets extend.

2. In a car roof, in combination, roof sheathing, a portion of said roof sheathing being gained out at each eaves edge; a flashing secured on said gained out sheathing; roof sheets disposed on opposite sides of the ridge, said roof sheets having side flanges, said side flanges extending from the ridge to a point short of the eaves and the unflanged portions of said sides of the roof sheets extending outwardly forming extensions of said sheets, the eaves edges of said roof sheets terminating in flanges depending over the edge of the roof sheathing, said flanges having a longitudinally extending outwardly pressed rigidifying head, the extensions of adjacent roof sheets being lapped, anchors secured at the eaves edges of the roof sheathing at the sides of adjacent roof sheets, said anchors having a top web and depending sides spaced from each other, said sides terminating in outwardly extending flanges, the lower portions of said sides having slots therein in which the extensions of said roof sheets are arranged; and seam caps enclosing the sides of said roof sheets and the anchors therebetween.

3. In a car roof, in combination: roof sheathing, flashing strips arranged thereon, roof sheets disposed on opposite sides of the ridge of the roof, anchors arranged between the sides of adjacent roof sheets, said anchors having a portion depending over the side of the car and secured thereto, seam caps enclosing the sides of adjacent roof sheets, said roof sheets having extensions on each side engaging said anchors.

4. In a car roof, in combination: roof sheets disposed on opposite sides of the ridge of the roof, an anchor arranged between adjacent sheets and secured to the side of the car, a portion of each of said roof sheets engaging said anchors and seam caps enclosing the sides of adjacent roof sheets.

5. In a car roof, in combination: roof sheets disposed on opposite sides of the ridge of the roof, an anchor arranged between ad-

jaçent sheets and secured to the side of the car, a portion of each of said roof sheets engaging said anchors and seam caps enclosing the sides of adjacent roof sheets and 5 the anchor therebetween.

6. In a car roof, in combination: roof sheets, an anchor between adjacent roof sheets, each of said anchors having a portion depending over the side of the car and 10 secured thereto, a slot therein, said roof sheets each having a portion engaging in the slot of an adjacent anchor.

7. In a car roof, in combination: roof sheathing, flashing strips arranged thereon; 15 roof sheets disposed on opposite sides of the ridge, said roof sheets having side flanges, said side flanges extending from the ridge to a point short of the eaves and the unflanged portions of said sheets forming extensions thereof, the eaves edges of said roof sheets terminating in flanges depending over the edge of the roof, an anchor arranged between adjacent roof sheets at the eaves of 20 the car, said anchor having a portion depending over the side of the car and secured thereto; said anchors having slots therein into which the extensions of the roof sheets extend and seam caps enclosing the side edges of adjacent roof sheets.

8. In a car roof, in combination: roof sheathing, flashing strips arranged thereon; roof sheets disposed on opposite sides of the ridge, said roof sheets having side flanges, said side flanges extending from the ridge to 25 a point short of the eaves and the unflanged portions of said sheets forming extensions thereof, the eaves edges of said roof sheets terminating in flanges depending over the edge of the roof, said depending flanges having 30 an outwardly pressed rigidifying bead therein and the flanges of adjacent roof sheets being lapped, an anchor arranged between adjacent roof sheets at the eaves of the car, said anchor having a member secured 35 to the side of the car below said eaves flange, said anchors having slots therein into which the extensions of the roof sheets extend and seam caps enclosing the side edges of adjacent roof sheets.

9. In a car roof, in combination: roof sheathing; a portion of said roof sheathing being gained out at each eaves edge, a flashing secured on said gained out sheathing; roof sheets disposed on opposite sides of the 45 ridge, said roof sheets having side flanges extending from the ridge to a point short of the eaves edge of the roof, and the unflanged portions of said roof sheets forming extensions thereof, the eaves edges of said roof 50 sheets terminating in flanges depending over the edge of the roof, said flanges having a longitudinal stiffening bead formed therein,

anchors secured to the side of the car and at the sides of adjacent roof sheets, seam caps enclosing the side flanges of adjacent roof sheets and the anchor therebetween, said anchor engaging the roof sheets to hold them down on the roof independently of said seam caps.

10. In a car roof, in combination: roof 70 sheathing; roof sheets disposed on opposite sides of the ridge, said roof sheets having side flanges extending from the ridge to a point short of the eaves edge of the roof and the unflanged portions of said roof sheets 75 forming extensions thereof, the eaves edges of said roof sheets terminating in flanges, anchors secured to upwardly extending portions of the car and at the sides of adjacent roof sheets, seam caps enclosing the side 80 flanges of adjacent roof sheets and the anchor therebetween, said anchor engaging the roof sheets to hold them down on the roof independently of said seam caps.

11. In a car roof, in combination: roof 85 sheathing; a portion of said roof sheathing being gained out at each eaves edge, a flashing secured on said gained out sheathing, roof sheets disposed on opposite sides of the ridge, said roof sheets having side flanges 90 extending from the ridge to a point short of the eaves edge of the roof, and the unflanged portions of said roof sheets forming extensions thereof, the eaves edges of said roof sheets terminating in flanges depending 95 over the edge of the roof, said flanges having a longitudinal stiffening bead formed therein, anchors positioned at the eaves edges of said roof sheathing and at the sides of adjacent roof sheets, said anchors being secured to the car below the eaves flanges of the roof sheets, seam caps enclosing the side 100 flanges of adjacent roof sheets and the anchor therebetween, said anchor engaging the roof sheets to hold them down on the roof. 105

12. In a car roof, in combination: roof sheathing, roof sheets disposed on opposite sides of the ridge, said roof sheets having side flanges extending from the ridge to a point short of the eaves edge of the roof and 110 the unflanged portions of said roof sheets forming extensions thereof, the eaves edges of said roof sheets terminating in flanges, anchors positioned at the eaves edges of said roof sheathing and at the sides of adjacent 115 roof sheets, said anchors being fastened to side portions of the car, seam caps enclosing the side flanges of adjacent roof sheets and the anchor therebetween, said anchor engaging the roof sheets to hold them down on the 120 roof.

In testimony whereof I have hereunto set my hand.

FRANCIS A. JACOBS.
